UNITED STATES PATENT OFFICE.

MARCUS FINKELSTEIN, OF NEW YORK, N. Y.

CLOTHES-STAND.

1,188,921.

Specification of Letters Patent. Patented June 27, 1916.

Application filed August 17, 1915. Serial No. 45,905.

To all whom it may concern:

Be it known that I, MARCUS FINKELSTEIN, a citizen of the United States, and a resident of the city of New York, borough of Manhattan, in the county and State of New York, have invented a new and Improved Clothes-Stand, of which the following is a full, clear, and exact description.

This invention relates to stands and particularly to a stand for clothes, as for instance, hats, coats, pants, or ladies' clothing, and has for an object the provision of an improved arrangement whereby the clothes will be held in proper position and some of the clothes stretched.

Another object in view is to provide a stand with an adjustable transverse bar for accommodating the same to different size coats, the same being associated with supporting and stretching means for a pair of trousers.

In the accompanying drawing:—Figure 1 is a side view of a stand embodying the invention; Fig. 2 is an edge view of the upper part of the stand shown in Fig. 1; Fig. 3 is a fragmentary sectional view through the stand shown in Fig. 1, the same being taken on line 3—3; Fig. 4 is an enlarged detail fragmentary perspective view showing one end of the supporting arm of the stand; Fig. 5 is a detail fragmentary sectional view through Fig. 1 approximately on line 5—5; Fig. 6 is a view similar to Fig. 3 but showing a slightly modified form of the invention; Fig. 7 is an edge view similar to Fig. 2 but showing an arrangement of hat brackets provided on the stand.

Referring to the accompanying drawing by numerals, 1 indicates a base of any desired kind to which is connected a standard 2, said standard being hollow, at least for part of its length, for accommodating the spring 3. A slot 4 is provided opposite the hollow portion of the standard so that the pin 5 may extend therethrough, said pin being connected with a sliding block 6 which is normally held in the position shown in Fig. 5 by spring 3. A hook 7 is adapted to be hooked over the pin 5 when a pair of trousers are arranged on the stand, said hook being connected with a clamp 8 clamping the lower end of the trousers 9. The normal position of the pin 5 as shown in Fig. 6, is an appreciable distance below the lower end of the trousers 9 so that the pin 5 and block 6 must be moved upwardly

against the action of spring 3 until the clamp 8, which may be of any desired construction, engages the lower end of trousers 9, whereupon the spring 3 will act on the trousers for maintaining the same stretched and thus kept in proper condition.

The upper end of the trousers 9 is engaged by any desired number of clamps 10, which clamps are provided with hooks 11 designed to hook over the transverse bar 12 and be supported thereby, bar 12 being rigidly connected with the standard 2 in any desired manner. Preferably the bar 12 is hollow at the outer ends or hollow for its full length as may be desired. A spring 13 is arranged adjacent each outer end, said spring acting on the inner end of the shoulder member 14 for urging the same outwardly. The shoulder members 14 freely reciprocate in the end of the bar 12 and are provided with pins 15 which project through slots 16 so as to engage the adjustable plate 20 which is provided with a slot 21. A clamping screw 22 extends through slot 21 and engages the bar 12 so as to clamp the plate 20 in any desired position. When the parts are arranged as shown in Fig. 4 the shoulder members 14 may be moved inwardly a short distance but cannot move outwardly. If it should be desired to allow the shoulders 14 to extend outwardly farther than shown in Fig. 4, screw 22 is loosened and plate 20 adjusted to the desired position and screw 22 again tightened. The shoulders can then move as far as the plate 20 will permit, plate 20 acting as a stop for limiting the outward movement of the shoulders but not affecting the inward movement. By providing the screw 22 and slot 21 the plate 20 may be locked in any desired position along the slot 16 so as to allow the shoulders 14 to be adjusted for fitting different size garments.

If desired, hat racks or brackets 17 and 18 may be provided, as shown in Fig. 7, the same being connected either to the cross bar 12 or to the standards 2 in any desired manner. Preferably, brackets 17 and 18 are connected with standard 2, or at least centrally of the stand, so as not to interfere with the coat or with the trousers while allowing a free use of the brackets.

In Fig. 6 will be seen a slight modified arrangement of spring 4' which is connected to the standard 2 by means of a pin 19. The spring 4' is rigidly connected with the

follower or sliding block 6 but acts as a retractile spring for holding this member in a lower position and thereby holding in a stretched condition the trousers 9. The 6 function of the structures shown in Figs. 5 and 6 is the same but the springs act in different directions.

It is evident that other slight changes may be made in the arrangement near base 10 1 without departing from the spirit of the invention.

It will also be evident that the arrangement of the locking means for shoulders 14 could be varied without changing the 15 principle of spring-pressed and adjustable shoulder members for fitting coats or other garments of different sizes.

What I claim is:—

1. In a clothes stand of the character described, a standard, a cross bar arranged adjacent the upper end of said standard, movable shoulder members arranged in said cross bar, said shoulder members being adapted to support a coat or the like, a 25 spring for each of the shoulder members for giving said members a tendency to move outwardly, and adjustable means for limiting the outward movement of the shoulder members without interfering with the inward movement thereof.

2. In a clothes stand of the character described, a supporting standard, a cross member arranged adjacent the top thereof, said cross member having hollow ends, an ad-

justable shoulder member extending into each of said hollow ends whereby the cross member may be varied in length for accommodating coats or other garments of different sizes, a spring acting on each of said shoulder members for resiliently holding the same in an outer position, and an adjustable plate arranged adjacent each of the shoulder members for limiting the movement of the shoulder members in one direction.

3. In a clothes stand of the character described, a standard, a cross bar formed hollow at the ends and having longitudinally arranged slots adjacent each end, a pair of shoulder members extending into said hollow ends, each of said shoulder members having a pin, said pins extending through said slots, a spring at each end acting on said shoulder members for urging the shoulder members outwardly, a limiting plate arranged adjacent each end of said cross bar adapted to engage said pins for limiting the outward movement of said pins, and means for clamping the plates in any desired adjusted position.

In testimony whereof I have signed my name to this specification in the presence of two subscribing witnesses.

MARCUS FINKELSTEIN.
